(57) **CLAIM**

The ornamental design for a video calling camera, as shown and described.

DESCRIPTION

FIG. 1 is a top, front and left side perspective view of a video calling camera showing my new design;
FIG. 2 is a bottom, back and right side perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines shown in the drawings, depict portions of the video calling camera that form no part of the claimed design.
